UNITED STATES PATENT OFFICE.

FRANK L. OHLER, OF TOLEDO, OHIO, ASSIGNEE TO THE HAUGHTON ELEVATOR AND MACHINE COMPANY, OF TOLEDO, OHIO, A CORPORATION OF OHIO

GATE-OPERATING DEVICE.

1,180,600.

Specification of Letters Patent. Patented Apr. 25, 1916.

Application filed March 24, 1915. Serial No. 16,533.

To all whom it may concern:

Be it known that I, FRANK L. OHLER, of Toledo, Lucas county, Ohio, a citizen of the United States of America, have invented 5 new and useful Gate-Operating Devices, of which the following is a specification.

This invention relates to control mechanism and the actuating connections therefor.

This invention has utility when embodied 10 in automatic mechanism for controlling and actuating gates in connection with elevators.

Referring to the drawings: Figure 1 is a fragmentary perspective view of an embodiment of the invention in connection with 15 an elevator car, elevator well having openings, and the gates for the openings; Fig. 2 is a fragmentary perspective view showing the car holding the gate operating mechanism for gate opening; Fig. 3 is a detail of 20 elements for rendering the gate actuating means effective; Fig. 4 is a section on the line IV—IV, Fig. 3, looking in the direction of the arrow; Fig. 5 is a plan view of the gate operating motor and control connections therefor; Fig. 6 is a fragmentary 25 side elevation of features of the motor control shown in Fig. 5; Fig. 7 is a view on the line VII—VII, Fig. 5, looking in the direction of the arrow; and Fig. 8 is a wiring 30 diagram of the control connections.

In the elevator shaft or well 1 is disposed the car or elevator 2 movable to various openings 3 or floor levels. Carried by the car 2 is a cam or holding device 4, which 35 when the car 2 is at a floor level, engages a roller 5 on the pivoted arm 6 to throw the dog 7 into engagement with the tooth 8 fast with the pulley block 9 carrying the pulley 10 riding in the bight or flexible 40 branch 11 passing over guide pulleys 12, 13, to a gate 14 for an opening 3. The branches or bights 11 are connected to the flexible actuating means or cable 15 extending 45 to the drum 16 on the shaft 17 having the worm wheel 18 driven by the worm 19 from the electric motor 20. Cable 21 passing 50 over the guide pulley 22 to the counterweight 23 serves to neutralize the load of the blocks 9 and one gate on the actuating cable 15. Gates upon different sides of the elevator well 1, or gates at other remote points may be controlled by this same motor or driving means 20, say by line 24.

Conveniently located in the car 2 is the

switch 25 connected by the line 26 to the 55 supply wire 27 of a three phase alternating current electric circuit. With this switch 25 thrown for bringing a lifted gate to down or closed position, the switch closes circuit from the line 26 through the line 28, 60 coil 29, line 30 to terminal or contact 31 traveling on the section 32 of the contact plate. The other contact plate connections are now considered. Electric current is conducted through the contact plate from the 65 section 33, contact 34, line 35, coil 36 to the supply wire 37, being the second wire of the three phase alternating current electric circuit. The third wire 38 of the alternating 70 current electric circuit is connected by the line 39 contact 40 to section 41 of the contact plate to complete electrical connection through the section 32 and contact 31 during the earlier travel of the plate toward gate closing position, and the contact 75 34 during the later travel of the gate.

The coil 36 when energized serves to close the switch 42 thereby connecting up the lines 43, 44, 45, as the power circuit to the motor for actuating the car 2. Accordingly 80 power can be supplied for actuating the car 2 only when the gates have been thrown for closed position by the switch 25 which in the travel of the plate to close a circuit through the contacts 33, 34, allows current 85 to flow through the coil 36. The coil 29 closes the switch 46 when energized, so that the supply wire 38, may have circuit closed from the line 47, 48, through the lines 49, 50 to the motor 20; and from supply wire 90 57, by lines 51, 52, through the lines 53, 54, as second lead to the motor 20, the third wire 55 therefrom extending to the supply wire 27. The coil 56 between the lead wires 54, 55, may release the brake for permitting 95 the motor 20 to operate.

The wiring diagram, Fig. 8, shows the control connections in position for the gate fully down, and as the terminal 31 has passed off the contact plate section 32, the 100 coil 29 is deenergized, while the contact 34 having moved upon contact plate section 33, the coil 36 is energized to close the switch for the main elevator motor. With the car 2 at a floor level or landing, the 105 switch 25 may be shifted to close circuit from the line 26 through the line 57 through the coil 58 line 59, contact 60 closing cir-

cuit through the plate sections 61, 41, and contact 40. The coil 58 so energized raises the switch 62, and through the lever 63 acts to insure that the switch 46 is open. The switch 62 closes electric circuit from the lines 37, 51, 64, through the lines 65, 50 to the motor 20; from the lines 38, 47, 66, through the lines 67, 54, for actuating the motor 20 in a reverse direction. In this 10 operation of the motor 20, the worm 19, acting through the worm wheel 18 drives the shaft 17, carrying the drum 16. The cable 15 is connected to the drum 16 to hang radially thereof at starting position, so that 15 the speed of travel of the gate to be lifted shall be lowest near its closed position. With the car 2 having its cam 4 in position to throw a dog 7 into engagement with a tooth 8, a pulley block 9 is held, while the 20 other pulley blocks 9 ride upward at half speed as the cable 15 is wound on the drum 16. The held block 9 causes the bight 11 extending therethrough to lift the gate 14 to which it is connected. As to the other 25 gates 14, the blocks 9 being lighter than the gates, the blocks only are lifted by the cable 15.

The shaft 17 carrying the drum 16 for winding the cable 15 in lifting the gate, 30 has thereon a threaded portion 68 the effective extent of which is determined by two adjustable clamp nuts 69, 70 (Fig. 6), each having an inwardly projecting lug 71. Mounted on this threaded portion 68 is the 35 loose nut or segmental gear 72 having lugs 73, 74, disposed to abut the lugs 71. Coacting with the gear segment 72 is the segment 75 (Fig. 7), having the flexible or spring arm 76 tending normally to maintain the 40 contact plate 32, 41, 61, 33, fast therewith in a medial position, and through the meshing relation with the nut 72, permit this nut 72 to travel along the threaded portion 68 during the rotation of the shaft 17. Say 45 the lug 71 will move away from the lug 72, thereby allowing the spring 76 to act to bring the contact plate and segment 75 to the central position (Fig. 7). The circuit through the coil 36 is broken and the power 50 lines cut off from the main elevator motor so the elevator may not be started until the gate is returned to closed position. When the rotations of the shaft 17 have just about completed opening the gate of the held 55 block 9, and the other blocks 9 are sliding upward on the guide 77, the lug 71 contacts the lug 74 to effect rocking of the contact plate to be free of the contact 60, thereby leaving only contacts 31, 40 on the 60 contact plate 32, 41, 61, 33. This shifting of the contact plate away from contact 60 de-energizes the coil 58, thus opening the switch 62 to automatically stop the motor 20, notwithstanding the switch 25 has been given 65 no attention. The only way left to throw

the switch 25 is for bringing the gate down, and this will effect the connection through the switch 46 reversing the motor 20 for such driving action. The device in its interrelation is so safety checked as to preclude 70 doing the wrong thing. Opening switch 25 will stop a traveling gate 14 at once.

What is claimed and it is desired to secure by Letters Patent is:

1. A traveling car, a cam carried by the 75 car, gate actuating means provided with connections to the gate independently of the position of the car, and means actuated by the cam on the car to render the actuating means effective to actuate the gate by coacting with the connection intermediate the gate and actuating means. 80

2. A traveling car, a cam carried by the 85 car, a plurality of gates, actuating means provided with connection to the gates independently of the position of the car, and a plurality of means actuatable by the cam on the car to render the actuating means effective by coacting with the connection intermediate the gate and actuating means. 90

3. A traveling car, a cam carried by the 95 car, a gate, flexible actuating means provided with connection to the gate independently of the position of the car, and means actuated by the cam on the car to render the actuating means effective to actuate the gate by coacting with the connection intermediate the gate and actuating means. 100

4. A traveling car, a cam carried by the 105 car, a gate, actuating means operable independently of car travel including a bight connected to the gate, and means actuated by said cam to engage the bight.

5. A traveling car, a cam carried by the 110 car, a gate, actuating means operable independently of car travel including a bight connected to the gate, a block in the bight, and means actuated by the cam on the car to engage the block. 105

6. A traveling car, a cam carried by the 115 car, a gate, actuating means operable independently of car travel including a bight connected to the gate, a pulley block in the bight, and a dog actuated by the cam on the car to engage the block.

7. A gate operating device including first actuating means for a gate provided with normally uninterrupted connection therewith, second guide means intermediate the extent of the connection between the gate and the actuating means for rendering the actuating means effective, and a holding device to engage the second means against relative travel. 120

8. A gate operating device including first actuating means for a gate provided with connection thereto, second guide means intermediate the extent of the connection between the gate and actuating means for rendering the actuating means effective, a hold- 125

ing device to engage the second means against travel, and a movable member for actuating the device.

9. A gate operating device including 5 actuating means for a gate provided with connection thereto, a dog intermediate the extent of the connection between the gate and actuating means for rendering the actuating means effective, and a cam holding 10 the dog against disengagement.

10. A gate operating device including a 15 cable having a bight, a pulley block in the bight, a dog for locking the block against relative travel, and a cam for throwing the dog.

11. An operating device for a plurality of gates including an actuating cable operable independently of car travel connected to the gates, said cable having bights therein, 20 blocks in the bights, and means for engaging a block to render the cable effective for actuating a gate.

12. An operating device for a plurality of gates including a plurality of bights, an 25 operating cable to which said bights are

connected, a gate connected to each bight, a block in each bight, and means for holding a block to render the cable effective to actuate the gate for that block.

13. A gate operating device including a 30 line having a bight, a pulley in the bight, a car movable past the gate, means coacting with the car to control the pulley and means operable independently of car travel for actuating the line to effect shifting of 35 the gate.

14. An electric motor, a plurality of gates provided with connecting means to the motor, and means intermediate the extent of the connecting means between a gate and 40 the motor for rendering operative the connection of such gate to the motor to effect movement of such gate by the motor.

In testimony whereof I affix my signature in the presence of two witnesses.
